(57) **CLAIM**

The ornamental design for a nozzle, as shown and described.

DESCRIPTION

FIG. 1 is a perspective view of a nozzle, showing my new design, as seen from above and in front;

FIG. 2 is a front elevational view as seen from below and in front thereof; left, right, and rear elevational views are identical to this view;

FIG. 3 is a cross sectional view taken along a central axis of symmetry of the device of FIGS. 1 and 2;

FIG. 4 is a top elevational view of the nozzle of FIG. 1;

FIG. 5 is a bottom elevational view of the nozzle of FIG. 1;

FIG. 6 is a perspective view similar to that of FIG. 1, as viewed from the top and left; and,

FIG. 7 is a perspective view of the device similar to that of FIG. 1, as viewed from below and to the right.
